US00D948870S

(12) **United States Design Patent** (10) **Patent No.:** **US D948,870 S**
Loudenslager et al. (45) **Date of Patent:** **** Apr. 19, 2022**

(54) **STRAP**

(71) Applicant: **YETI Coolers, LLC**, Austin, TX (US)

(72) Inventors: **John Loudenslager**, Austin, TX (US);
John W. Dow, Austin, TX (US); **Derek G. Sullivan**, Austin, TX (US)

(73) Assignee: **YETI Coolers, LLC**, Austin, TX (US)

(**) Term: **15 Years**

(21) Appl. No.: **29/729,148**

(22) Filed: **Mar. 24, 2020**

(51) **LOC (13) Cl. 03-01**

(52) **U.S. Cl.**

USPC **D3/327; D3/318**

(58) **Field of Classification Search**

USPC D3/318, 321-324, 327, 232-246;
D9/434, 443; D11/201; D30/153
CPC .. A44C 5/18; A44C 5/20; A44C 5/185; A45C 1/024; A45C 1/10; A45C 3/00; A45C 3/06; A45C 3/08; A45C 5/00; A45C 5/03; A45C 5/04; A45C 5/14; A45C 13/00; A45C 13/08; A45C 13/10; A45C 13/26; A45C 13/30; A45F 3/02; A45F 3/04; A45F 5/00; A45F 5/10; A45F 5/14; B25H 3/02

(57) **CLAIM**

The ornamental design for a strap, as shown and described.

DESCRIPTION

FIG. 1 is a top, front, right perspective view of a strap showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of a strap shown in an exemplary environment.

The zig-zag lines and even-length broken lines within the shaded area represent stitching that forms no part of the claimed design. The even-length broken lines and the uneven-length broken lines immediately adjacent to the shaded area define the bounds of the claimed design form no part of the claimed design.

1 Claim, 4 Drawing Sheets
